AUTOMATIC PRESSURIZED FIRE
EXTINGUISHER

Ronald H. Mascarini, Kearny, N. J.

Application April 2, 1952, Serial No. 280,070

6 Claims. (Cl. 169—26)

1

My invention relates generally to fire extinguishers and specifically to improvements in automatic pressurized fire extinguishers adapted to disseminate a fire extinguishing fluid over a wide area.

It is among the objects of my invention to provide an improved automatic pressurized fire extinguisher which is sensitive, safe, and sure acting.

It is among the further objects of my invention to provide an automatic pressurized fire extinguisher which is simple in form, sure acting and relatively inexpensive to maintain, assemble, install and operate.

Yet another object of my invention is to provide an automatic pressurized fire extinguisher which stores the fire extinguishing fluid under normal pressure.

Still a further object of my invention is to provide a fire extinguisher which has a discharge nozzle which is adapted to disseminate its contents over a wide area.

Yet another object of my invention is to provide a fire extinguisher which is simple to rearm and refill.

These objects and advantages, as well as other objects and advantages, are achieved by the device illustrated in the drawings, in which:

Figure 1 is a side view of my fire extinguisher;

Figure 2 is a vertical cross-sectional view of my fire extinguisher showing it in its ready state;

Figure 3 is a vertical cross-sectional view showing it in its activated state;

Figure 4 is a view in perspective of the cartridge bracket;

Figure 5 is a side view of the plug and shaft connected therewith;

Figure 6 is a side view of the retainer;

Figure 7 is a side view of the clip;

Figure 8 is a side view of the fusible links; and

Figure 9 is a view in perspective of the retainer, clip and link assemblage.

Referring now to the drawings in detail, my fire extinguisher is formed of a container 11. A discharge nozzle 12 is formed at the bottom of the container. A wall 13 separates the discharge nozzle 12 from the main portion of the container 11. The wall 13 has a fluid passage 14 in the center. The fluid passage is surrounded by a seat 15 which is adapted to receive a plug 16. The plug 16 and seat 15 constitute a valve for containing or releasing a fluid in the container 11. A bracket 17 is attached to the container 11 by being screwed into a threaded passage 18 in the wall 13. The bracket 17 has a guide arm 19 extending over the passage 14. A shaft 20 is slidably positioned in a passage 21 in the guide arm 19, and is attached to the plug 16. The lower side of the plug has a corresponding shaft 22. A spring 23 carried by the shaft 20 normally urges the plug 16 into blocking engagement with the seat 15 defined by the walls of the fluid passage 14. This spring 23 bears on the bottom of the arm 19 and the top of the plug 16.

2

Another spring 24, which is stronger than the spring 23, and carried by the shaft 22, normally urges the plug 16 upward and unseats it. This spring 24, is held by the U-shaped retainer 25 whose legs 26 pass through the bottom of the container 11 and are held in this position by a spring clip 27 whose ends are held together by the links 28. The links are held together by a low melting point solder 29. When sufficient heat melts the solder 29, the links 28 separate, the spring clip 27 opens, and falls off the notches 30 on the legs 26 where it was seated. The retainer 25 then releases the spring 24, which then unseats the plug 16, permitting any fluid in the container to enter the discharge nozzle 12, and leave through the holes 31.

The bracket 17 has a channel 32 formed in an extended portion 33. A resilient guide 34 having out-turned ends 35 will slide into this channel. The top of the shaft 20 has a cup-like seat 38 for a CO₂ cartridge 39 which the guide 34 holds loosely in place. The top of the bracket 17 has an arm 36 which is provided with a piercer 37.

The container 11 is provided with a lid 40 which screws on to seal the container. The center of the lid 40 has an opening 41 into which a filler cap 42 is screwed. The outer top edge 43 of the container has a thread which will engage a corresponding threaded flange on the attachment plate 44. The attachment plate 44 may be secured by screws 45 (or in some other suitable manner) to the ceiling or roof.

My fire extinguisher is installed by affixing the attachment plate 44 to the roof or ceiling by screws 45, or in some other desired manner. The container is then armed by causing the retainer 25 to compress the spring 24 so that the legs 26 extend through the bottom of the discharge nozzle 12. The spring clip 27 is then applied to the legs 26 and seated in the notches 30. The spring clip is compressed and the fusible links 28 slipped over the ends. This permits the light spring 23 to function and to seat the plug 16 to firmly block the fluid passage 14. The CO₂ cartridge 39 is then placed upon the seat 38 and the resilient guide is slid down around the cartridge into the channel 32. A light spring 48 will keep the top of the cartridge from striking the piercer 37 should the container 11 be inverted. The container 11 may then have its lid 40 applied. The plug 42 may be removed and a fire extinguishing fluid inserted to a suitable level. Observation of the level of the extinguishing fluid may be made through the window 47. The plug may then be restored and the container 11 screwed into the attaching plate 44.

A rise in temperature will cause the separation of the fusible links 28. The spring clip 27 springs open and disengages itself from the notches 30. This releases the spring 24 which will raise the plug 16 so that the fire extinguishing fluid goes through the fluid passage 14 into the discharge

nozzle 12. The rising of the plug 16 impelled by the strong spring 24, compresses the lighter spring 23. The CO₂ cartridge 39 is urged upward by the seat 38 on which it rests and is forcibly brought in contact with the piercer 37. This releases the carbon dioxide gas in the cartridge and creates pressure in the container 11 so that the fire extinguishing fluid is urged out of the container into the discharge nozzle under considerable pressure. The pressure forces the fire extinguisher fluid 46 out of the holes 31 under considerable pressure and sprays it to a substantial distance from the container 11. The fire extinguisher may thereafter be rearmed in the same manner in which it was loaded as previously described.

The foregoing description is merely intended to illustrate an embodiment of the invention. The component parts have been shown and described. They each may have substitutes which may perform a substantially similar function; such substitutes may be known as proper substitutes for the said components and may have actually been known or invented before the present invention; these substitutes are contemplated as being within the scope of the appended claims, although they are not specifically catalogued herein.

I claim:

1. A fire extinguisher comprising a valve, a first spring normally urging the valve open, a second spring of less strength than the first spring normally urging the valve closed, a bracket having upper and lower arms, a shaft attached to the valve and extending through the lower arm, a seat defined by the top of the shaft, a cartridge of compressed gas positioned on the seat and cooperatively movable therewith, a piercer depending from the upper arm, and a heat-reactive means for releasably securing the first spring.

2. A fire extinguisher comprising a valve, a first spring normally urging the valve open, a second spring of less strength than the first spring normally urging the valve closed, a retainer engaged with the first spring, a clip engaged with the retainer and holding it in compressing relationship with the first spring, links engaged with the clip and holding it in engagement with the retainer, material having a predetermined fusion point holding the links together, a first shaft depending from the valve, a second shaft rising from the valve, a seat defined on the top of the second shaft, a cartridge of compressed gas positioned on the seat and cooperatively movable therewith, a bracket, upper and lower arms on the bracket, the second shaft passing through the lower arm, and a piercer depending from the upper arm.

3. A fire extinguisher comprising a container, a nozzle formed at the bottom of the container, a wall separating the nozzle from the container having a fluid passage defining a seat, a plug adapted to engage the seat, a shaft depending from the plug, a spring carried by the shaft and normally acting to unseat the plug, a retainer for the spring, a clip engaged with the retainer to maintain it in compressing relationship with the spring, links engaged with the clip and holding it in engagement with the retainer, material having a predetermined fusion point holding the links together, a shaft rising from the plug, a guide arm for the shaft, a seat defined at the top of the shaft rising from the plug, a cartridge of compressed gas positioned on the seat and

cooperatively movable therewith, a spring carried by the shaft rising from the plug and normally urging the plug into engagement with the fluid passage defining a seat, said spring exerting less force than the spring carried by the shaft depending from the plug, and a piercer positioned over the discharge end of the cartridge.

4. A fire extinguisher comprising a container, a nozzle with a plurality of openings formed at the bottom of the container, a well separating the nozzle from the container having a fluid passage therein defining a tapered seat, a tapered plug adapted to engage the seat and block the fluid passage, a shaft depending from the plug; a spring carried by the shaft bearing on the nozzle and normally acting to unseat the plug; a retainer carried by the shaft and over the top of the spring, notched legs on the retainer extending through the wall of the nozzle; a clip position outside the nozzle and engaged with the notches of the retainer to maintain the spring compressed, said clip being resilient and normally extended wider than the legs of the retainer, links engaged with the clip, material having a predetermined fusion point holding the links together, a shaft rising from the plug, a bracket attached to the wall, a guide arm having a passage for the shaft rising from the plug, a seat defined at the top of the shaft rising from the plug and cooperatively movable with the plug, a cartridge of compressed gas positioned on the seat, a spring carried by the shaft rising from the plug bearing on the guide arm and normally urging the plug into engagement with the seat, said spring exerting less force than the spring carried by the shaft depending from the plug, an arm on the bracket extending over the cartridge, and a piercer mounted on the arm for engagement with the discharge end of the cartridge.

5. A fire extinguisher comprising a valve, a first spring engaged therewith, a heat reactive means for securing the first spring from normally urging the valve open, a second spring of less strength than the first spring normally urging the valve closed, a bracket having upper and lower arms, a shaft attached to the valve and extending through the lower arm, a seat defined by the top of the shaft and cooperatively movable with the valve through the action of the first spring, a cartridge of compressed gas positioned on the seat, and a piercer depending from the upper arm.

6. A fire extinguisher comprising a chamber for a fire extinguishing fluid, a valve in the said chamber for releasing the said fluid, a seat for a cartridge of compressed gas cooperatively connected with the valve whereby the opening of the valve moves the seat, a cartridge of compressed gas positioned on the seat, a piercer in alignment with the discharge end of the cartridge, a spring normally urging the valve open whereby the opening of the valve moves the seat and projects the cartridge into piercing engagement with the piercer.
